(57) **CLAIM**

The ornamental design for a bag, as shown and described.

DESCRIPTION

FIG. 1 is an isometric view showing the front, top and one side of my invention;

FIG. 2 is an isometric view showing the top and rear of my invention with the bag open;

FIG. 3 is a front elevation view of my invention;

FIG. 4 is a rear elevation view of my invention;

FIG. 5 is a top elevation view of my invention;

FIG. 6 is a bottom elevation view of my invention;

FIG. 7 is a left-side elevation view of my invention; and,

FIG. 8 is a right-side elevation view of my invention.

In the drawings the shading on the handle is intended to indicate a difference in texture between the handle and body of the bag.

In the drawings the shading on the body of the bag is intended to indicate the suppleness of the body of the bag.

The broken lines shown on the drawings are included for the purpose of illustrating stitching and are part of the claimed design.
